KNOT-TYING DEVICE

Thomas Charles Bromley and Guy Storr Helliswell, Leicester, England, assignors to Mellor Bromley and Company Limited, Leicester, England, a British company

Application May 28, 1935, Serial No. 23,912
In Great Britain June 1, 1934

13 Claims. (Cl. 289—3)

This invention relates to knot-tying devices of the type having a rotary tying head which includes a tying bill and such as are used in the textile and knitting arts for mechanically tying together the ends of threads, yarns and strands by a small knot, usually a knot of similar formation to a weaver's knot.

The invention is mainly applicable to knot-tying devices, hereinafter termed knotters, of the hand-operated kind such as are carried upon one hand and actuated by a thumb lever or trigger after the threads, yarns or strands, herein-after termed yarns, have been laid across the knotter in the yarn receiving guides thereof. The invention is not, however, limited in its application to hand-operated knotters as it may be embodied in or applied to a mechanically-actuated knotter.

In knotters of the particular kind concerned the threads to be knotted together are laid by hand across the knotter and are received in open guide slots in the opposite side members of the device. Prior to the tying operation of the rotary tying head the threads require to be crossed in order that the bill of the tying head and the threads can become so related that one thread lies to the back and the other to the front of the tying bill with the two threads crossing each other on one side of the bill i. e. between the bill and the adjacent side of the device.

Moreover, in knotters of the particular kind concerned the knot after being tied by and about the tying bill is stripped off the bill by a stripper member which has associated with it a scissor device, said stripper and scissor device being movable relatively to the tying bill.

The principal object of the invention is to provide an improved knotter of the type referred to which will obviate the difficulties commonly experienced incidental to the preliminary crossing of the threads and will be capable of use in a very simple manner not calling for any particular skill or more than ordinary care on the part of the operator.

A particular object of the invention is to provide a knotter of the type concerned in which the two yarns to be knotted upon being laid by the operator into open-ended slots in opposite sides of the device will become crossed in relation to the tying bill preparatory to being acted upon by the latter.

It is a further object of the invention to improve knotters of the kind concerned with a view to ensuring that the knot when stripped from the bill of the rotary tying head shall be

clear of the bill during the return motion of the tying head.

In the accompanying drawings,

Figure 1 is a side elevational view of the main part of a hand-operated knot-tying device including examples of the improvements provided by this invention.

Figure 2 is a front end elevation of the same.

Figure 3 is a view similar to Figure 1 but showing the opposite side of the device.

Figure 4 is a detail perspective view illustrating the threads to be joined laid across the knotter.

Figure 5 is a rear view of the device as viewed in the direction of the arrow in Figure 1 with the threads laid across the mechanism as in Figure 4.

Figure 6 is a view similar to Figure 5 illustrating the initial rotation of the tying bill which brings the latter into contact with the threads.

Figure 7 is a detail perspective view illustrating the mechanism of the device in a subsequent stage of its operation and showing the clamping means acting upon the threads.

Figure 8 is a view similar to Figure 1, on a larger scale, illustrating the device with the plates at one side thereof removed and showing more particularly the improved scissor device and stripper.

Figure 9 is a similar view but showing the knotter at the end of its operation.

Figure 10 is a detail view representing the scissor device and stripper in end elevation.

Like parts are designated by similar reference characters throughout the drawings.

Referring to the drawings, 2 represents the rotary tying head which includes a tying bill 2a and 3, 3 the side members in which the front and rear receiving guide slots 4 and 4a respectively of the device are formed.

In the improved knotter according to a convenient embodiment of the invention, the axis of the tying head shaft 2b has an angular relationship to the guide slots 4, 4a of less than 90° (for example about 45°). Moreover, in relation to the bill 2a of the tying head 2, which normally occupies a downwardly turned position (for example about the four o'clock position as shown in Figures 2, 4 and 5) the guide slots 4 and 4a in the sides 3 of the device are formed so that the threads are laid over the tying head, each thread a being supported at a higher point in one side than in the other the high point of support of one thread being in one side of the device and

the high point of support of the other thread being in the other side of the device.

In each side of the device the two guide slots are substantially upright and open at the top 5 for laying of the threads *a*, the slot 4 being situated in front of the slot 4a as hereinbefore stated. In the side of the device shown in Figure 1 the rear slot 4a is carried lower than the other and in the other side of the device the front slot 4 is carried lower than the other. When the threads *a* are laid across the knotter the rear thread is laid in the rear guide slots 4a and the front thread is laid in the front slots 4. Viewed from above the knotter and looking down in the 10 line of the slots the two laid threads are parallel or substantially so but, as owing to the different depth of the slots in the opposite sides in which each thread is laid the rear thread is high in one side and low in the other, while the front thread 15 is low in the one side and high in the other viewed from the front (see Figure 2) i. e. at right angles to the guide slots, the two laid threads present a crossed appearance.

Now, the axis of the tying head shaft 2b is 20 at such an angle to the guide slots 4 and 4a that looking down upon the laid threads from above the knotter and at about right angles to the axis of the tying head 2 (see Figure 5) the two threads are seen stretched across from side to 25 side of the device in crossed relation over the tying head with the bill 2a in such position that upon commencing to move upwards it can pass between the crossed threads, as represented in Figure 6, without any preliminary manipulation 30 of said threads. That is to say, the threads *a* and bill 2a are so relatively positioned normally by the simple act of laying the threads across the device in the open slots that upon the rotation of the tying head commencing, the tying 35 bill can enter between the threads at a point between that where they are crossed and the adjacent side of the device, as clearly shown in Figure 6.

Advantageously, as shown more clearly in Figure 4, the guide slots are positioned so that the 40 rear threads when laid lies above and clear of the tying head 2 and the front thread when laid is situated in front of and clear of the rear thread and over but touching that side of the tying bill 45 2a which is presented uppermost when the bill is in the four o'clock position. With this arrangement, when the tying head 2 commences to turn anticlockwise, the bill 2a at about the three o'clock position gets in front of the front thread 50 (see Figure 6), at about the two o'clock position enters between the threads and at the twelve o'clock position has the front thread passing behind it and the rear thread on the front of it the 55 said two threads crossing each other on opposite sides of the bill as seen when looking down upon the threads from above the knotter.

The improved knotter is arranged with the tying bill—looking at the front of the device—occupying normally about the four o'clock position and revolving anticlockwise to form the knot.

The two threads are tensioned in the left side of the device as considered when regarding Figure 2, these being the threads which are tied (the 60 ends in the right side being subsequently cut off).

In the arrangement shown for laying the two threads to be tied across from left to right i. e. with the ends in the right side of the knotter (looking at the front end), the bottom of the rear slot 4a in the left side is lower than the bottom

of the front slot 4 in the same side (see Figure 1), and the bottom of the rear slot 4a in the right side is higher than the bottom of the front slot 4 in this side, as represented in Figure 3.

The side of the knotter which holds the two threads to be tied will for sake of convenience be hereinafter referred to as the tie side while the other side which holds the ends which are to be cut away after or when the knot is formed will be referred to as the cut side.

It has already been stated that either side of the device may be made the tie side the other side being the cut side. Now, on the tying side of the tying head 2, the threads require to be held so that they may be tensioned as the tying head 15 operates to tie the knot and for this purpose the improved knotter is furnished with means which tension the threads without however changing their position in the side in relation to each other or to the tying head; that is to say the threads 20 are tensioned while they remain supported by the bottoms of the guide slots in which they are laid. This feature of the invention is carried out in the arrangement shown in the drawings by making the tie side of the knotter device two-walled 25 and providing between the walls 3a, 3b a mechanically moved member having parts which when the member is moved pass across the guide slots and co-act with the adjacent parts of the side walls and thus act upon the threads *a* in the guide slots to clamp them lightly for tensioning purposes. One or each of the walls 3a, 3b is resilient or they are arranged to spring apart so that a yielding clamping action upon the threads between the said walls and member is 30 provided thus obviating injury to the threads.

In the constructional example illustrated of this feature of the invention the tie side of the knotter consists as stated of two plates 3a, 3b with a movable member 5 of thin plate-like form 40 between them the outer plates 3a, 3b being held or pressed into contact with the intermediate plate-like member 5 but capable of springing away from it. The said outer plates may be attached by screws or rivets 6 to a body block 45 7 forming the centre part of the knotter device between the tie side and the cut side. The intermediate plate-like member 5 is, as shown, in the form of a lever suitably actuated and having parts 5a and 5b which when the lever is in the 50 normal position, shown more clearly in Figure 1, leave the guide slots—which are formed in both plates 3a, 3b constituting the tie side—open for the threads *a* to be laid therein but which parts 55 when the lever is actuated move across the slots so as to act on the threads *a* and nip or bend them between the plates to hold or tension the threads in the tie side of the device.

As will be seen the said lever 5 has a bifurcated end the opening 5c which is normally in register with the long rear slot 4a in the tie side of the device and which bifurcation receives the rear thread when this is laid in said slot. When the lever 5 is moved the bifurcation is moved out of register with the slot 4a and, as shown in Figure 7, thus clamps the threads *a* between the lever and adjacent plates 3a and 3b. One side of the bifurcated end of the lever 5, that is to say the part 5b of the latter, normally projects above the plates 3a and 3b or wall of the tie side thus forming a portion separating the front slot 4 from the rear slot 4a in the tie side. The plates 3a and 3b in this case have a small rounded part 3c upstanding between the slots and the rear edge of the front slot 4 in each plate is notched 70 75

at the bottom to receive the thread when it is pushed back by the action of the lever 5. The rear edge or part 5a of the bifurcated end of the lever serves as the member for acting upon the 5 thread a in the rear slot 4a to clamp same.

On the cut side of the tying head 2 the threads a require to be changed in position during the tying operation and this may be done by any suitable mechanical means.

10 For example, and as shown, the cut side of the device is also composed in a similar manner to the tie side of two plates 3d and 3e but, as represented more clearly in Figure 3, has two intermediate movable members one a pusher 8 for pushing the front thread forward and the other a presser 9 for pressing the rear thread downwards as shown in Figure 7. The knotter is also provided with other elements for completing the knotting operation such as a rising and falling auxiliary scissor device and a tightening and stripper element of suitable form, and the various movable mechanical elements of the improved knotter may be actuated by any convenient means. The knotter has a thumb lever or trigger 10 which turns a spring-controlled semi-circular member 11 mounted upon a transverse axis and having on one side and integral therewith a toothed arcuate rack or sector 11a engaging teeth on the tying head shaft 2b to rotate the latter. The knotter as hereinbefore described has a central body block 7 to which the sides are attached and in which the tying head shaft 2b is journaled; the said body block also carries the transverse axle 11b on which the 35 aforesaid semi-circular member 11 oscillates. The movable member 2c of the tying head is actuated by a vertical cam 2d attached to the body block 7, and is controlled by a pin 2e fixed in the tying head upon which pin a slot 2f in 40 the movable member works.

The pusher and presser members 8 and 9 respectively between the plates 3d and 3e of the cut side are actuated from a rock lever 12 carried by the body block 7. The said rock lever is 45 moved by a cam slot 11c in the semi-circular member 11 which acts on a pin 12a on one end of the rock lever the opposite end of which latter has pivotally attached to it the rear end of the pusher member 8 which is a thin plate-like element having a forward notched end 8a and an upstanding limb 8b intermediate of its ends. The presser member 9 is a small rocker pivotally mounted by a pin 9a on the inner plate 3e of the cut side and having a hook-shaped front extremity or nose while its rear end is slotted. A pin 8c on the side of the limb 8b of the pusher member 8 passes through the slot 9c in the presser rocker and also through a slot 3f in the inner plate 3e of the cut side. When the rock 55 lever 12 is moved to push the pusher 8 forward the connecting pin 8c operates the presser rocker and rides along the slot 3f in the inner plate which slot and the arcuate movement of the rear end of the pusher member 8 determine the path 60 of movement of the front notched end 8a thereof.

The thread tensioning lever 5 between the plates 3a and 3b of the tie side is also moved by the above-mentioned pin 12a on the rock lever 12 from which the pusher and presser members are 65 actuated.

When the parts described are in normal position as represented in Figure 3, the notch of the pusher 8 is in register with or below the bottom of the front slot 4 in the cut side and the hooked nose of the presser rocker 9 is withdrawn be-

hind the rear edge of the rear slot 4a. It should be here mentioned that the guide slots 4 and 4a are formed in the outermost plate 3d only of the cut side; the inner plate 3e of this side of the device has a little notch 3g formed in it at a 5 point below the bottom of the rear slot 4a in the outer plate 3d while the portion 3h of the inner plate in front of the front slot 4 in the outer plate is cut away.

As will be seen, the upper open ends of the 10 guide slots 4, 4a are flared or widened to facilitate the laying of the threads a therein. Moreover, in order to prevent the threads from being laid in the wrong slots, a rigid right-angled extension 3i is formed on the outer plate 3d between the slots 4 and 4a on the side of the device. In using the knotter described the two threads are laid across from left to right one in the rear pair of slots 4a and the other in the front pair 4, the tying bill occupying about a 20 four o'clock position as shown more clearly in Figure 4. All that the operator need do is to pull the threads down to the bottom of the slots which are straight and upright or mainly so in the device as represented in position for use. 25

As hereinbefore stated, it is also a feature of the invention that the usual scissor device, designated by 13, is carried independently of or separately from the stripper, designated by 14. In the example shown more clearly in Figures 8, 30 9 and 10, it will be seen that the scissor device is carried by a separate lever.

Describing the arrangement more fully, the bodily movable scissor device 13 (comprising three scissor blades two 13a of which are fixed 35 and the other 13b is movable therebetween and relatively thereto) is carried by a lever 15 pivotally mounted on the central block or body portion 7 of the knotter which lever is disposed longitudinally and in a plane parallel to the axis 40 of the rotary tying head 2. This lever 15 is situated in a vertical plane towards one side of the knotter and at its front end it has an integral or rigid extension 15a at right angles to the main body of the lever and transverse to the axis of 45 the rotary tying head (see Figures 2 and 10), which extension at its end remote from the lever has a downwardly extending part 15b forming an elongated lug disposed in a plane parallel to the main portion of the lever. To the outside 50 of this lug the blades 13a of the scissor device 13 are attached such as by a screw 13c and a pin 13d so as to be stationary on the lug, and the blade 13b located between said blades 13a is adapted to turn on the said pin 13d and co-operate with the fixed blades for yarn-severing purposes. As will be seen the screw 13c is arranged so as to permit of adjustment of the angle of the fixed scissor blades 13a relatively to the movable blade 13b. The fixed blades are, as shown, 55 sprung into close contact with the movable blade. The front end of the lever 15 is so shaped that when it rises the lever will pass up on one side of the tying bill 2a and the scissor device 13 will pass up on the other side of the bill as seen in 60 Figure 10.

At a suitable point between the fulcrum and the front end of the scissor lever 15 just referred to there is pivotally mounted on the inside of said lever a second lever 16 the front end of which 70 has a right-angled extension 16a similar to and adapted to come on the inside of the extension 15a on the scissor lever. This second lever is the stripper lever and its right-angled extension has hereon an upstanding finger 16b the upper 75

end of which is hollowed, notched or hooked to engage one of the tied threads when the stripper rises. The end of the stripper lever extension 16a remote from the said lever terminates in a small lug 16c in the outside of which is fixed a pin or stud 16d engaging a slot 13e in the adjacent pivoted blade 13b of the scissor device on the extension 15a of the other lever 15. The upstanding finger 16b on the stripper lever extension 16a is disposed thereon so as to rise on the opposite side of the tying bill 2a to that where the scissor device is situated as represented in Figures 2 and 10.

The stripper lever 16 is pivoted 16b for free rocking movement on the scissor-carrying lever 15 but such movement is controlled by a pin 7a fixed in the block or body portion 7 of the knotted at a suitable position in front of the fulcrum of the scissor lever. This pin is engaged by the rear end of the stripper lever which end is slotted at 16e to slide on the fixed pin as the levers rise and fall; this distance between the pivot of the stripper lever 16 on the scissor lever 15 and the fulcrum of the latter is greater than the distance between said pivot and the fixed pin 7a during any part of the movement of the levers, consequently as the stripper lever 16 is carried and moved by the scissor lever 15, the former is caused to move relatively to the latter and the parts are so arranged that during the upward motion of the same the front end of the stripper lever 16 will rise quicker than the front end of the scissor lever 15. The relative movement between the stripper lever 16 and scissor lever 15 during the upward and downward movements of both is utilized by the pin and slot connection (16d, 13e) already referred to, to operate the movable blade 13b of the scissor device 13 the parts being so arranged that as the scissor device rises it closes and as it falls it opens. Figure 8 shows the scissor device in the fully open position whilst Figure 9 shows the same in the fully closed position. By the arrangement described the stripper can be given a movement in excess of the associated scissor device for the purpose of effectively pulling the tied knot from the bill 2a and removing it to a remote position to be clear of the bill during return rotation of the tying head 2.

As shown the rising and falling movements of the scissor lever 15 is imparted by the thumb lever or trigger 10 of the knotted which, as hereinbefore mentioned, is integral with a spring-controlled semi-circular member or quadrant 11 mounted upon a transverse axle in the knotted the said member having on one side thereof two pins 11d and 11e one 11d normally situated in an arcuate open-ended slot 15c in the underside of the scissor lever and the other 11e appropriately positioned to pass, when the semi-circular member or quadrant 11 is turned, on the underside of the rear end 15d of the scissor lever and to engage with a notch 15e in the latter near the fulcrum to turn said lever and raise the front end.

The arrangement of the operating means just described is such that when the knotted is at rest prior to use, the pin 11d on the semi-circular member or quadrant 11 occupies a normal position within the arcuate slot 15c of the scissor lever and thus holds the latter from turning movement on its fulcrum and the other pin 11e at this time is in a position rearward of the rear end 16d of the scissor lever. The said rear end 75 of the lever which extends beyond the fulcrum

is curved on its underside which curved part and the aforesaid slot 15c are concentric with the axis of the semi-circular member or quadrant when the scissor lever 15 is in normal position as shown in Figure 8. As usual, the stripper 5 and scissors are normally below the tying head 2.

Upon the thumb lever 10 being depressed the tying bill 2a moves from normal position in an anticlockwise direction until on reaching the twelve o'clock position it has the two threads in 10 the position previously described viz. the front thread at the back of the bill and the rear thread on the front of the latter. Prior to this, however, when the bill reaches about the three o'clock position the aforesaid pusher 8 and presser 9 in 15 the cut side commence to operate, the former moving forward and the nose of the latter moving downward, which action continues until the tying bill reaches about the six o'clock position (see Figure 7), by which time the nose of the presser 20 9 has pushed the rear thread down into the little notch 3g in the inner plate 3e on the cut side and the notch 8a of the pusher 8 has pushed the front thread forward beyond the bottom of the guide slot 4. The latter part of the movement of the pusher is slightly upward as well as forward so that the notch 8a which acts on the thread 9 lifts the latter as well as pushes it forward. The pusher 8 and presser 9 having shifted their respective threads co-act with the adjacent 30 plates 3d and 3e to hold or tension them.

Moreover, as soon as the bill 2a moves from the normal four o'clock position the lever 5 between the plates 3a and 3b of the tie side moves to tension the threads and by the time the bill has 35 reached the nine o'clock position (not shown) both threads are held or tensioned in the tie side. In Figure 7, the lever 5 is shown as coming into operation.

Upon passing from the nine o'clock position the 40 tying bill 2a enters between the two threads on the tying side at a point between the said tie side and where the two threads are crossed and upon rising from the six o'clock (Figure 7) to the second three o'clock position (not shown) the bill 45 2a, the members or jaws of which are open, finds the threads on the cutting side presented in such a position by the aforesaid pusher 8 and presser 9 after their described movements that on rising from the second three o'clock position it can 50 take the rear thread between its open jaws and bring the front thread onto the outside front of the bill 2a which relationship is attained at about the two o'clock position. Rotation of the tying head 2 continues and the scissor lever now 55 commences to rise and as the tying bill nears the twelve o'clock position the upstanding finger 16b on the stripper lever comes up under the front thread on the tying side of the bill and gets said thread into its notch while at the same time the open scissor device 13 is rising with the finger 16b gets the front thread on the other side of the bill between its blades 13a and 13b. At about the one o'clock position the bill members close thereby severing the rear thread on the cutting 60 side and clamping the other end. As the bill 2a moves from the one o'clock to the 12 o'clock position the notched finger 16b of the stripper and the scissors 13 move higher with the result that the said finger pushes the front thread upwards 70 thereby tightening the knot and moving it up the bill. At about the time that the bill reaches the twelve o'clock position, the scissors 13 sever the front thread on the cutting side of the bill and the finger 16b completes its rise to pull the knot 75

off the upper pointed extremity of the bill which on the completion of the operation, represented in Figure 9, is in about the ten o'clock position after the tying head has made one and a half 5 revolutions or thereabouts. As regards the operation of the scissor device and stripping element, upon the semi-circular member or quadrant 11 being turned by pressure applied to the thumb lever or trigger 10 the pin 11d thereon 10 moves down along the open ended slot 15c in the scissor lever 15 and prior to its passage out of said slot the pin 11e assumes a position underneath the arcuate rear end 15d of the scissor lever and as the turning motion of the semi-circular 15 member or quadrant continues, the pin 11d passes out of the open ended slot and the pin 11e follows the pin 11d and passes along the concentric underside of the lever thereby preventing turning motion of said lever in one direction after 20 the pin 11d having left the slot has ceased to control it. Turning of the lever 15 in the other direction is prevented by a suitable abutment 7b on the block or body portion 7 of the knotter. While the pin 11e is moving under the concentric rear 25 part 15d of the scissor lever 15 the latter remains stationary but after a time the said pin strikes a projecting part on the underside of the lever near the fulcrum and adjacent the notch 15e and thereby turns the lever on its fulcrum thus elevating the stripper 14 and scissor 13. The arcuate underside of the rear end 15d of the lever and the aforesaid projecting part form a corner into which the pin passes and in this corner there is as aforesaid a notch or recess 15e with which the 30 pin 11e may engage and in which it may work as the lever turns on its fulcrum. As shown more clearly in Figure 9 the rise of the stripper is limited by a peg 11f formed on the semi-circular member or quadrant which peg abuts against the block 35 or body portion 7 of the knotter at the end of the operation of the latter. After the knot has been stripped from the bill the two threads *a* which have been tied remain held by the tension lever 5 in the guide slots 4, 4a in the tie side of the device but upon the thumb lever 10 being released the spring returns the semi-circular member 11 backwards thereby restoring all the elements to normal position and releasing the threads which can be lifted out from the slots. The 40 downward motion of the scissor lever 15 is effected by the pin 11e on the semi-circular member or quadrant 11 acting in the notch or recess 15e and against the arcuate rear portion 15d of the lever which restores the latter to normal position and holds there until the pin 11d enters and assumes its original position within the open 45 ended slot 15c.

Referring again to the relative disposition of the thread receiving guide slots 4 and 4a and the 50 tying head 2 which is one of the distinguishing features of the invention, it may be stated that with the device in a position wherein the thread receiving guide slots are vertical as shown more clearly in Figure 1, the rotary tying head shaft 2b is disposed with its axis inclined downwardly and rearwardly from the tying bill end. A suitable angle of inclination for this axis is about 45° but this may vary. The tying bill is at about 90° to the tying head shaft as usual, consequently 55 owing to the aforesaid inclination of the tying head shaft when the tying bill stands up in the twelve o'clock position it is tilted or inclined backwards at about an angle of 45° to the vertical guide slots in the sides of the device. In the 60 known forms of knotters of the kind concerned

where the rotary tying head shaft is disposed horizontally the tying bill is parallel to the slots when in the twelve o'clock position.

In a knotter constructed according to the present invention the knotted yarns are free to be removed from the knotter immediately the stripping operation is completed and before the thumb lever or trigger is released. This is an advantage in that it saves time and entirely precludes the possibility of the tied yarns becoming caught by the moving parts of the knotter as they return to their initial positions.

What we claim then is:—

1. In a knot-tying device, a rotary tying head which includes a tying bill, a scissor device, a 15 stripper device for stripping the knot from the tying bill, one of said devices being carried by a lever pivotally mounted in the knotter, and the other device being carried by another lever mounted upon the first mentioned lever so as to 20 enable differential movement to be effected between the scissor device and the stripper device, means for moving the two devices in company, and means for effecting movement of the stripper device at increased speed in relation to the 25 scissor device when the two devices are moved in company.

2. In a knot-tying device, a central body portion, a rotary tying head mounted in said body and having a tying bill, a lever carrying a scissor device, said lever being movable relatively to said bill and pivotally mounted on said body portion, means for operating said lever, a stripper lever carried by said scissor carrying lever and a control pin on the central body portion 30 adapted to engage said stripper lever to effect 35 a differential movement between the two levers when the scissor lever is moved for the purpose described.

3. In a knot-tying device, a central body portion, a rotary tying head mounted in said body and having a tying bill, a lever carrying a scissor device which latter includes a movable slotted blade, said lever being pivotally mounted on said body portion in a plane parallel to the axis of 40 the tying head, means for operating said lever, a stripper lever carried by said scissor carrying lever, a pin on said stripper lever adapted to engage the slot in the movable blade of the scissor device, and a control pin formed on the central body portion and arranged in such relation 45 to the scissor lever fulcrum as to engage said stripper lever and effect a differential movement between the two levers, such movement being utilized to actuate the said movable scissor blade. 50

4. In a knot-tying device, a central body portion, a rotary tying head mounted in said body and having a tying bill, a main operating member pivotally mounted in said body and adapted to rotate the tying head, a lever carrying a 60 scissor device which latter comprises fixed blades and a relatively movable slotted blade said lever being pivotally mounted on said body portion in a plane parallel to the axis of the tying head, a stripper lever carried by and pivoted upon 65 said scissor carrying lever, a pin on said stripper lever adapted to engage the slot in the movable blade of the scissor device, a control pin arranged in the central body portion so as to engage said stripper lever and effect a differential movement between the two levers, which movement also actuates the said movable scissor blade, and means on the main operating member for controlling and effecting the movement of said scissor carrying lever. 70

5. A knot-tying device comprising in combination a central body block, two side members attached to said block and each comprising two plates adapted to spring away from each other, 5 two substantially straight guide slots being formed in each side member of the device to receive the threads to be tied, the bottom of one of said slots in each side member being lower both than the other slot in the same member 10 and than the opposite slot in the other side member, a rotary tying head located between said members in an inclined position relatively to said slots, a tying bill on said head normally occupying a downwardly turned position, an intermediate plate-like member mounted to move between the two plates of the member at one side of the body block and having parts which when said intermediate member is moved pass across the guide slots at that side and co-act with the 15 adjacent parts of the plates to clamp the threads lightly for tensioning purposes during the tying operation without however changing their position in relation to each other and to the tying head, a pusher member and a presser member 20 mounted to move between the plates of the other side member for changing the positions of the threads during the same time, means for operating the clamping member and the pusher and presser members, a stripper member for stripping the knot from the tying bill, a scissor device carried independently of the stripper, and means for operating the stripper member and the scissor device in such a manner that when the two are moved in company the former is 25 moved at an increased speed relatively to the latter.
6. In a knot-tying device, a rotary tying head, which includes a tying bill, a stripper member movable relatively to said bill and adapted to 30 strip the knot from the latter, a scissor device associated with said stripper member but carried independently thereof, means for moving said scissor member at an increased speed relatively to the scissor device during the movement of 35 the scissor device and stripper member in company for cutting purposes and for stripping the knot from the bill.
7. A knot-tying device comprising, in combination, a central body portion, a side member at each 40 side of said body portion, each of said side members having two guide slots therein to receive the threads to be tied, the bottom of one of said slots in each side member being lower than the opposite slot in the other side member, a rotary 45 tying head located between said members and in an inclined position relatively to said slots, a tying bill on said head normally occupying a downwardly turned position, means for holding the threads at one side of the knotter to tension 50 the same during the tying operation without, however, changing their positions in relation to each other and to the tying head, means at the other side of the device for changing the position of said threads during the same time, a lever 55 carrying a scissor device, a stripper lever movable relatively to the tying bill and having a part adapted to strip the knot from said bill, said

stripper lever being pivoted for free rocking movement on the scissor-carrying lever, means for controlling and effecting movement of said scissor-carrying lever, and a control pin on the central body portion, said pin being arranged in 5 such relation to the scissor carrying fulcrum as to engage said stripper lever and effect a differential movement between the two levers when the scissor-carrying lever is moved, for the purpose described.

8. A knot-tying device, comprising two side members, each having two thread receiving slots therein, one of said slots in each side member being deeper than the other, and the deeper slot in one member being opposite the shallower 15 slot in the other side member, a rotary head located between said side members and having a shaft which is obliquely disposed in relation to the guide slots and a tying bill on said head extending at right angles to the tying head shaft and 20 normally occupying a downwardly turned position.

9. A knot tying device, comprising two side members, each having two thread receiving slots therein, one of said slots being deeper than the 25 other, and the deeper slot in one side member being opposite the shallower slot in the other member, a rotary head located between said side members and having a shaft which is obliquely disposed in relation to the guide slots and a tying 30 bill on said head extending at right angles to the tying head shaft and normally occupying a downwardly turned position, said slots being so disposed relatively to the tying head that the threads to be tied may be laid therein in crossed relation, 35 transversely to the axis of the shaft in a direction at right angles to the slots.

10. A knot tying device as set forth in claim 9, in which the shaft of the tying head has an angular relation to the thread receiving slots of 40 90° the arrangement being such that when the threads to be tied are laid in the slots they may be extended in cross relation transversely to the axis of the tying head shaft.

11. A knot tying device, as claimed in claim 9 45 and having means for tensioning the threads on one side of the device during the tying of the knot, said means being arranged and adapted to yieldingly act on said threads.

12. A knot tying device comprising two side 50 members each having two thread receiving slots therein one of said slots in each member being deeper than the other, the deeper slot in one member being opposite the shallower slot in the other member, means, including a tying head for 55 tying a knot in the threads and means on one side of the device arranged and adapted to tension the threads on one side of the device without changing their position in relation to each other or to the tying head.

13. A knot tying device as claimed in claim 12 60 having on one side movable members adapted and operable to change the position of the threads during the tying operation.
